Primary Examiner—Louis S. Zarfus**Assistant Examiner**—I. Simmons**Attorney, Agent, or Firm**—Gary L. Griswold; Walter N. Kirn; Stephen W. Bauer**[57]****CLAIM**

The ornamental design of a cassette for arthroscopic irrigation system tubing set, as shown and described.

DESCRIPTION

FIG. 1 is a perspective view of a cassette for arthroscopic irrigation system tubing set showing our new design;

FIG. 2 is a top plan view thereof;

FIG. 3 is a front elevational view thereof;

FIG. 4 is a right side view thereof;

FIG. 5 is a left side view thereof;

FIG. 6 is a rear elevational view thereof; and,

FIG. 7 is a bottom plan view thereof.
